UNITED STATES PATENT OFFICE

148,765

DESIGN FOR A FOLDING CAMERA

Theodore G. Clement, Rochester, N. Y., assignor
to Eastman Kodak Company, Rochester, N. Y.,
a corporation of New Jersey

Application April 24, 1947, Serial No. 138,587

Term of patent 14 years

(Cl. D61—1)

To all whom it may concern:

Be it known that I, Theodore G. Clement, a citizen of the United States, residing at Rochester, in the county of Monroe and State of New York, have invented a new, original, and ornamental Design for a Folding Camera, of which the following is a specification, reference being had to the accompanying drawings, forming a part thereof, in which

Fig. 1 is a perspective view taken from the front and slightly to one side of a folding camera in its folded position and showing my new design.

Fig. 2 is a perspective view similar to Fig. 1 of the camera in a closed position being taken from the back and toward one side and of the camera shown in Fig. 3.

Fig. 3 is a perspective view showing the camera in an open position and taken from the front and slightly toward one side and showing my new design.

I claim:

The ornamental design for a folding camera, as shown.

THEODORE G. CLEMENT.
